SWITCH BOX

Application filed June 6, 1924. Serial No. 718,326.

In electric distribution systems it is customary to provide switches and cut-outs with connections for meters and for house wires and to enclose these in a box or casing so designed that the fuses can be replaced only when the switch is open. This is for safety and also to prevent the stealing of current. My invention aims to provide a box cover for use in connection with such fuse and switch mechanisms. The accompanying drawings illustrate an embodiment of the invention.

Fig. 1 is a plan of a box in the closed position;

Fig. 2 is a longitudinal section of the same with the cover lifted;

Fig. 3 is an elevation of the inside of the cover in the position of Fig. 2;

Fig. 4 is a side elevation of the upper part of Fig. 1.

Referring to the embodiment of the invention illustrated, the box 1 which carries the fuse and switch mechanism is provided with a cover 2 hinged at 3 and having a flange 4 which comes down over the edge of the box.

At the opposite end of the cover there is an opening 5 adapted to register with another opening 6 in the end wall of the box for the passage of a sealing wire or lock.

Within the box there is located an arm 7 arranged to rotate about a vertical axis indicated at dotted lines at 8 having at its end a socket 9 which receives a threaded fuse block 10. The other mechanism in the box is not illustrated, being well known and being possibly of any one of a great number of arrangements. When the arm is rocked to the position shown the switch or switches within the box are opened. When the arm is rocked in the direction of the arrow, Fig. 1, the switches will be closed.

The cover of the box has a raised central portion 11 at the center of which is a pivot 12 carrying on its inner end a lever for operating the mechanism. The lever is shown in Fig. 3 and comprises an arm 13 with a flange 14, (Fig. 2) adapted when the cover is down to embrace the end of the fuse socket 9 as indicated in dotted lines. The lever has a handle passing up through the cover, the portion 15 being on the inside of the cover and the oper-

ating portion 16 on the outside. It is stiffened by a rib 17 stamped into the sheet metal of which it is made. This rib 17 is so located as to prevent full closing of the cover 2 if the switch should be closed and the shutter set for the open position. In Fig. 1 the location of the rib 17 is shown dotted for the position of the shutter corresponding to the open switch, and the location of the fuse 10 is shown for the closed position of the switch, assuming the switch to have been closed while the cover 2 was lifted. When the cover 2 is brought down (with the shutter in the open position and the fuse 10 in the closed position) the rib 17 will strike the fuse 10 and prevent bringing the cover fully down and will thus apprise the operator that either the shutter or the switch should be shifted to bring the fuse into register with the flange opening 14 of the operating member.

The handle passes through a segmental slot 18 in the cover of sufficient length to permit it to swing in one direction to the position shown adjacent to an upright open stop 19 or in the opposite position adjacent to a second upright closed stop 20 on the top of the cover. The handle is apertured and the uprights 19 and 20 are also apertured so that in either position the handle may be tied to the adjacent upright and sealed or locked there.

On the outside of the central portion 11 of the cover and rotating also on the pivot 12, is a second cover or shutter 21 which has a flange 22 surrounding the raised part of the cover. The handle 16 passes through an opening in the outside shutter 21 which closely fits the handle so that the shutter must turn with the handle. The shutter has an opening 23 which registers with the opening formed by the flange 14 of the operating lever. The raised portion 11 of the cover has also an opening 24 which in the position shown registers with the openings in the shutter and in the operating lever respectively. Thus, when the cover is lowered with the flange 14 engaging the fuse socket and the parts in the open-switch position of Fig. 1, the fuse can be withdrawn through the several openings. Assuming the cover still down, the turning of the handle 16 to the opposite position will

swing the fuse socket to a point beneath an imperforate portion of the cover and close the switch; the opening 23 in the outside shutter swinging with the operating lever and fuse socket. In this position the switch is closed and access must be prevented from the outside. The provision of the outside shutter makes access absolutely impossible through the opening 24 of the cover. If it were not for this outside shutter, it is conceivable that a wire could be introduced through the opening 24 and through the narrow space left for necessary play between the cover and the operating lever and access thus obtained to some of the contacts within the box. But the outside shutter, particularly with its flange depending around the raised portion of the cover makes the insertion of a wire in this way out of the question.

The invention is shown applied to a switch and fuse mechanism employing a single fuse. It may be applied also to a plurality of fuses, with a corresponding number of apertures like 24 in the cover of the casing and a corresponding number of outside shutters, either as separate plates or as a single plate with the necessary number of apertures like 23 to register with those in the cover. The shutter of my invention is useful in connection with various other switch mechanisms where it is desired to open or shut the apertures in the cover as a switch is opened and closed, respectively whether the fuse sockets be movable or be otherwise rendered accessible. And while the invention is shown applied to an ordinary movable cover, yet it will be understood that it is applicable also to various other parts of the box which might in a general sense serve as covers for the mechanism.

Though I have described with great particularity of detail a certain embodiment of my invention, yet it is not to be understood therefrom that the invention is restricted to the particular embodiment disclosed. Various modifications may be made by those skilled in the art without departure from the invention as defined in the following claims.

What I claim is:—

1. A casing for switch and fuse mechanism including an apertured cover and a shutter on the outside of the cover adapted to be connected to the mechanism and to uncover the aperture when the switch is open and to cover it when the switch is closed, said cover having a raised portion in which the aperture is located and said shutter having a flange surrounding such raised portion of the cover.

2. A casing for switch and fuse mechanism including an apertured cover, a shutter and means for operatively connecting said shutter to said fuse mechanism so as by its movement to bring the fuse socket into register with the aperture in the cover and at the same time to uncover said aperture and to move the

fuse socket out of register and at the same time to cover said aperture, said shutter in the covering position having a portion overlapping said aperture on the outside.

3. A casing for switch and fuse mechanism including an apertured cover, an operating member mounted on the inside of the cover for opening and closing the switch and a shutter operatively connected with said operating member so as to close the aperture in the cover when the switch is closed and to uncover said aperture when the switch is open, said shutter in the closing position having a portion overlapping said aperture on the outside. 70

4. A casing for switch and fuse mechanism, including a fuse socket, said casing having a cover for opening and closing the casing, said cover having an aperture through it, a sliding shutter on the outside of the cover and movable therewith and having an aperture in line with the fuse socket and an operating member on the inside of the cover operatively connected with the shutter, said operating member adapted when the cover is closed to engage the fuse socket and when moved by said shutter to bring the fuse socket into and out of registry with said aperture in the cover. 80

5. A casing for switch and fuse mechanism, including a fuse socket, said casing having a cover for opening and closing the casing, said cover having an aperture through it, an outside shutter pivoted on the cover and having an opening adapted to be moved into and out of register with said aperture, a lever on the inside of the cover pivoted about the same axis as the outside shutter and having a handle passing up through the cover and engaging the outside shutter, said lever having a part adapted to engage the fuse socket and to move the same into and out of register with said aperture. 90

6. A casing for switch and fuse mechanism having a hinged cover with an aperture through it, an apertured shutter on the outside of the cover adapted in one position to have a solid portion overlying the aperture so as to prevent access therethrough to the inside of the box and in another position to have its aperture overlying that of the cover and means for operatively connecting said shutter and said mechanism so that when the shutter aperture overlies that of the cover the fuse is accessible and the switch is opened and in the reverse position of the shutter the switch is closed. 100

In witness whereof, I have hereunto signed my name.

EMIL T. HAGIST.
